UNITED STATES PATENT OFFICE.

THOMAS ROBERT GILLETT PARKER, OF ALTRINCHAM, ENGLAND, ASSIGNOR TO LINOTYPE AND MACHINERY LIMITED, OF LONDON, ENGLAND, A BRITISH LIMITED LIABILITY COMPANY.

MEANS FOR CLAMPING AND STRETCHING FLEXIBLE PLATES ON PRINTING-PRESS CYLINDERS.

Application filed March 11, 1924. Serial No. 898,351.

To all whom it may concern:

Be it known that I, THOMAS ROBERT GILLETT PARKER, a British subject, and resident of Linotype and Machinery Works, 5 Altrincham, in the county of Chester, England, have invented new and useful Improvements in Means for Clamping and Stretching Flexible Plates on Printing-Press Cylinders, of which the following is a 10 specification.

This invention relates to means for clamping and stretching flexible plates on printing press cylinders, and although especially applicable for use in connection with the 15 plate cylinders of web offset litho rotary presses, it can be used in connection with other types of press.

In a web printing press, the gap of the plate cylinder, within which a plate clamping and stretching device is located, must be 20 of no greater width than the width of the margins at the top and bottom of a printed page. For that reason it has heretofore been found somewhat difficult to accommodate 25 devices which will efficiently tighten the flexible plate about the periphery of the plate cylinder.

The present invention provides a new or improved construction which admits of the 30 device being conveniently housed within the limited available accommodation, and by which the plate can be placed under any desired degree of tension. To that end it comprises means whereby the two ends of 35 the plate (when the cylinder is clothed with only a single plate) or adjacent ends of different plates (when the cylinder is clothed with a plurality of plates) can be intersected within the gap, and drawn into the 40 gap, for tightening said plate or plates upon the cylinder, in the direction of planes intersecting within said gap.

To avoid undesirable circumlocution, the 45 following description is restricted to an arrangement wherein the press cylinder is clothed with two printing plates, but this is to be regarded merely as a convenient example, because the invention is equally applicable for use in connection with one plate 50 or more than two plates.

The invention will now be described by reference to the accompanying drawings

which represent one constructional form of said invention, and in which:

Figure 1 is a side elevation partly broken 65 away of a cylinder clothed with two plates;

Figure 2 is a view of the cylinder drawn to a different scale partly in end elevation and partly in transverse section, and

Figure 3 is a perspective view showing 60 conventionally how the adjacent ends of the plates cross each other in intersecting planes.

According to this invention, as shown best in Figure 3, the flexible plate 1, is provided with a number of recesses or notches 2 and projections 3, located in such positions as to admit of the interposition between the projections 3 of the projections 4 of an adjacent plate 5, and vice versa these 70 last named projections being produced by forming spaced recesses 6 in the same manner as is done in connection with the recesses 2 and projections 3. By these means the projections 3 of the plate 1 can be interposed between the projections 4 of the plate 5 and can cross each other either at right angles as illustrated, or at any other angle as may be found most convenient.

Within the press cylinder 7 just at the 75 inner side of each gap 8, there are provided two clamp bars 9, 10, each adjustable, in the example illustrated, at right angles to the other in guides 11, 12 respectively, formed in guide plates 13 fast to the two ends of 80 the press cylinder. Each of the clamp bars 9, 10, is fitted with a plate-clamping jaw 14, bolts or screws 15 for tightening said jaw on the plate 1 interposed between it and the clamp bar, and springs 16 or other means 85 for moving the jaw outwards from the clamp bar, when the bolts 15 are released.

As the adjustment of the two clamp bars 9, 10, is in directions intersecting each other at a point within the periphery of the cylinder 7 and it is desirable that they engage the flexible plate 1 as near as possible to said periphery, the adjacent edges of those bars are formed, like the edges of the flexible plates themselves, with projections adapted 90 to be mutually interposed, as shown best in Figure 2.

In each of the guide plates 13 there are journalled two screws 17 which engage with

the clamp bars 9, 10, in such manner that when they are rotated, they move said bars edgewise to tighten or slacken the flexible plate 1 on the press cylinder 7.

5. The screws 17 appertaining to the two ends of each clamp bar 9, 10, are rotated in unison by helical gear wheels 18 fast to the former, and meshing with similar wheels 19 fast on a shaft 20 journaled in the plate 10 cylinder 7, which shaft can be rotated by a key or spanner applied to either of its squared ends, and when so rotated, effects the tightening or loosening of the plate 1 around the cylinder 7.

15. Having described my invention, I declare that what I claim and desire to secure by Letters Patent is:—

1. The combination with a printing press cylinder, of flexible-plate clamping and 20 stretching means located within a gap in the cylinder, and adapted to draw into the gap, in the direction of planes intersecting within the cylinder, intersecting plate ends presented at that gap.

25. 2. The combination with a printing press cylinder having a gap for the reception of printing plate ends, of flexible-plate clamping and stretching means adapted to draw into the gap, in the direction of planes intersecting within the cylinder, intersecting plate-ends presented at the gap, said means being located within the cylinder beyond the line of intersection of said planes.

30. 3. The combination with a printing press cylinder and flexible-plate clamping and stretching means located within a gap in the cylinder, of a pair of plate ends presented at the gap, and spaced projections on the said ends adapted to be mutually interposed.

35. 4. The combination with a printing press cylinder having a gap adapted to receive printing plate ends, of two clamp bars located within the gap, spaced projections on 40 the two bars adapted to be mutually interposed, and a device adapted to move each such bar edgewise perpendicularly to the other bar.

45. 5. The combination with a printing press cylinder having a gap adapted to receive printing plate ends, of two clamp bars located within the gap, a device at each end of the cylinder adapted to move each such bar edgewise perpendicularly to the other bar, and means whereby both of said de-

vices can be operated simultaneously from either end of the cylinder.

6. The combination with a printing press cylinder having a gap adapted to receive printing plate ends and a pair of plate ends 60 presented at the gap, of spaced projections on the said ends adapted to be mutually interposed, two clamp bars located within the gap adapted to clamp the interposed projections of the plate ends, spaced projections 65 on the two bars adapted to be mutually interposed and a device adapted to move each clamp bar edgewise perpendicularly to the other clamp bar.

7. The combination with a printing press 70 cylinder having a gap adapted to receive printing plate ends, of two clamp bars located within the gap, spaced projections on the two bars adapted to be mutually interposed, a guide for each bar at each end of 75 the cylinder the guides for one bar being located at right angles to those for the other bar, and a device at each end of the cylinder adapted to adjust each bar along its guide.

8. The combination with a printing press cylinder having a gap adapted to receive printing plate ends, of two clamp bars located within the gap, spaced projections on the two bars adapted to be mutually interposed, a guide for each bar at each end of 85 the cylinder the guides for one bar being located at right angles to those for the other bar, a device at each end of the cylinder adapted to adjust each bar along its guide, 90 and means whereby the two adjusting devices of each bar may be operated simultaneously.

9. The combination with a printing press cylinder having a gap adapted to receive 95 printing plate ends, of two clamp bars located within the gap, spaced projections on the two bars adapted to be mutually interposed, a guide plate at each end of the cylinder, guides in the said plates located at 100 right-angles to each other and adapted to receive the ends of the respective bars, screws journaled in the guide plates and engaging the respective bars, and means adapted to rotate simultaneously the screws appropriate to each bar.

In testimony whereof I have affixed my signature hereto.

THOMAS ROBERT GILLETT PARKER.
